UNITED STATES PATENT OFFICE.

OSCAR L. ANDERSON AND CHARLES H. SKILLINGS, OF FLINT, MICHIGAN.

DIES.

1,147,839.

Specification of Letters Patent. Patented July 27, 1915.

Application filed November 9, 1914. Serial No. 871,095.

To all whom it may concern:

Be it known that we, OSCAR L. ANDERSON and CHARLES H. SKILLINGS, citizens of the United States of America, residing at Flint, 5 in the county of Genesee and State of Michigan, have invented certain new and useful Improvements in Dies, of which the following is a specification, reference being had therein to the accompanying drawings.

- 10 This invention relates to dies that have been especially designed for pressing and shaping sheet metal fenders, panels and body portions used in the manufacture of automobiles.
- 15 The primary object of our invention is to provide dies that possess a certain degree of yieldability in their fabrication that eliminates fractures, cracks and blemishes when excessive pressure is brought to bear upon 20 sheet metal between dies.

Another object of our invention is to provide dies of the above type that are simple in construction, inexpensive to manufacture, easy to manipulate in various kinds of 25 presses, and highly efficient for shaping sheet metal.

With the above and other objects in view the invention resides in a novel construction, combination and arrangement of parts 30 to be hereinafter specifically described and then claimed.

Reference will now be had to the drawing, wherein—

Figure 1 is a plan of a stationary die for 35 bending and shaping a side body panel; Fig. 2 is a side elevation of the same; Fig. 3 is an inverted plan of a movable die adapted to coöperate with a stationary die; Fig. 4 is a side elevation of the movable die; Fig. 5 is a cross sectional view of the dies; Fig. 6 is a perspective view of a side body 40 panel produced by the die; Fig. 7 is an inverted plan of a movable die designed for pressing and shaping fenders; Fig. 8 is a side elevation of the same; Fig. 9 is a plan 45 of a stationary die adapted to coöperate with the movable die shown in Figs. 7 and 8; Fig. 10 is a side elevation of the stationary die; Fig. 11 is a cross sectional view of the fender 50 die, and Fig. 12 is a plan, upon a small scale, of a fender produced by the die.

In describing our invention by aid of the views above referred to, we desire to point out that the same are intended as merely 55 illustrative of an example whereby our invention may be applied in practice, and we

do not care to confine our invention to the precise construction and arrangement of parts shown. The following description is therefore to be broadly construed as including substitute constructions and arrangements of parts which are the obvious equivalent of those to be hereinafter referred to.

Considering Figs. 1 to 6 inclusive, the reference numeral 1 denotes a pallet and suitably secured thereto is a die body 2, which is rectangular in plan and has a curved or concave shaping or bending surface 3. One end of the body 2 is necessarily of greater depth than the opposite end and it is at the deep 60 end of the body that a transverse body 4 is secured with filler or corner pieces 5. The two bodies form an inverted T shaped structure and the side and end walls of the structure are provided with flanging plates 6 65 bolted or otherwise connected to the structure, as at 7. The lower end of the body 2 is provided with a transverse groove 9 and a wear plate 8 adjacent said groove, said plate preventing the edge of the groove from being broken down, also assisting in holding a sheet metal plate while the same is beaded and flanged. A blank side body panel can be placed on the stationary die and pressed in the die to produce the panel shown in Fig. 70 80. The material forming the upper end of the panel is sufficiently upset by the flanging plate at the low end of the die as to enter the groove 9 and form a head or rib 10 at the upper outer edge of the panel. The flanging plates 6 provide the side edges and lower portion of the blank with a flange 11 and it is through the medium of this flange that the completed panel is connected to a door post. As the side edges of the panel assist in providing an automobile body with doorways, it 85 is necessary that certain portions of the flange 11 be disposed at an obtuse angle relative the body of the panel, therefore the plates 6 at the inner side of the body 4 are 90 disposed at an angle, as indicated at 12 thus permitting of the panel blank being properly shaped. Coöoperating with the stationary die just described is a movable die, comprising a pallet 13, a main body 14 and a 95 transverse body 15. The main body 14 has a curved or convex surface and said body is properly shaped to enter the stationary die. The bodies 14 and 15 are provided with marginal metallic strips 16 and at the large or 100 deep end of the body 14 is a bead 17 coöperating with the groove 9 in forming the bead

or rib 10 at the upper end of the side body panel. To guide the movable die in entering the stationary die, the stationary die has a plurality of guide posts 18, preferably located upon one side thereof in order not to interfere with the placing of a panel blank upon the stationary die. When the pallets 1 and 13 are mounted in a press or suitable machine and a panel blank placed upon the stationary die, the movable die when entering the stationary die simultaneously bends the blank to any desired curvature and flanges the edges thereof. With the die bodies made of wood, said bodies will yield before excessive pressure can fracture or injure the blank, it being essential that the bodies of the dies are made of material capable of yielding or less tenacious than the metallic plates 6 and the strips 16.

Reference will now be had to Figs. 7 to 12 inclusive showing dies that are similarly constructed to produce a fender 19 from a suitable fender blank. The stationary die shown in Figs. 9 and 10 comprises a pallet 20, a body 21, and flanging plates 22 bolted or otherwise secured to the guide walls of the body. Secured to the top of the body 21 by screws 23 or other fastening means are metallic plates and strips 24 having grooves 25 therein adapted to produce beads 26 upon a fender blank, when a movable die is pressed in the stationary die. The movable die comprises a pallet 27 and a body 28. Secured to the body 28 by screws 29 or other fastening means is a metallic plate 30 having the edges thereof flanged, as at 31 and suitably secured to the side walls of the body. The metallic plate 30 has beads 32 to coöperate with the groove 25 of the stationary die in forming the bead 26 upon the fender blank. At one end of the movable die is a flanging plate 33 that produces a flange 34 at the lower end of the fender, and the movable die has notches 35 in the pallet thereof to receive posts 36 of the stationary die. When the dies are brought together, the plate 33 produces a flange that extends in an opposite direction from the flanges produced by the flanging plates 22 and simultaneous with the flanging of the fender blank, said blank is provided with a stiffening bead 26. Beside the flanges of the

fender rounding off the edges thereof, said flanges coöperate with the body of the fender in providing a pocket or recess for a 55 filler or packing, and while we have herein illustrated the fender dies as being flat, it is apparent that the same can be readily constructed with a curvature, as suggested by the dies shown in Figs. 1 to 5 inclusive. In 60 either instance, the metallic flanging plates or strips are backed by a yieldable material and if the material yields only the fractional part of an inch it is sufficient to prevent fracture and cracking of the blank, particularly at the flanged edges thereof.

In using the terms "movable" and "stationary" as applied to the dies, it is to be understood that such terms are simply for the convenience of describing our invention 70 as it is possible to make either of the dies stationary or movable or both of the dies movable, it depending upon the type of press or machine in which the dies are placed. It is also to be understood that 75 other parts of a sheet metal automobile body can be readily shaped and pressed by dies especially designed in accordance with our invention.

What we claim is:—

1. Dies comprising wood bodies, metallic strips and plates carried thereby and adapted to reinforce said bodies and produce clean sharp lines, and flanging plates on said bodies adapted to produce flanges when 85 said dies are brought together.

2. Dies for shaping sheet metal parts adapted for automobiles, comprising a stationary wood body, flanging plates carried by walls thereof, a movable wood body 90 adapted to coöperate with said stationary body in shaping a blank placed between said bodies, and metallic strips carried by said movable wood bodies adapted to produce clean sharp lines when said dies are brought 95 together.

In testimony whereof we affix our signatures in presence of two witnesses.

OSCAR L. ANDERSON.
CHARLES H. SKILLINGS.
